UNITED STATES PATENT OFFICE.

HENRY LEIMAN, OF TAMPA, FLORIDA.

METHOD OF MAKING CIGAR-BOXES.

1,395,843.

Specification of Letters Patent.

Patented Nov. 1, 1921.

Application filed January 14, 1920. Serial No. 351,293.

To all whom it may concern:

Be it known that I, HENRY LEIMAN, a citizen of the United States, residing at Tampa, in the county of Hillsborough and State of Florida, have invented certain new and useful Improvements in Methods of Making Cigar-Boxes; and I do hereby declare the following to be a full, clear, and exact description of the invention, such as will enable others skilled in the art to which it appertains to make and use the same.

This invention relates to a method of making wooden boxes and the like, and particularly to the manufacture of cigar boxes. Its object is to facilitate the process of manufacture and to produce thereby a box of superior appearance and strength.

In the drawings,

Figure 1 is a plan view of a blank comprising a slab of wood of rectangular area proportioned to make a complete box without cover, and having a layer of paper cemented to it.

Fig. 1^a is an enlarged section through a portion of the blank shown in Fig. 1.

Fig. 2 is a view of the under side of the blank after the act of applying reinforcing strips has been performed.

Fig. 2^a is a section through the blank illustrated in Fig. 2.

Fig. 3 illustrates a blank after grooves have been cut in its upper surface.

Fig. 4 is a view of the blank shown in Fig. 3 after a binding has been applied to the edges.

Fig. 5 is a plan view showing the corner pieces detached.

Fig. 6 illustrates the condition of the blank during the bending of the parts to form the side walls.

Fig. 7 is a view of the box after the side walls have been joined and secured together.

Fig. 8 is a view of box and cover.

Fig. 9 is a detail of a corner.

Fig. 10 is a view of a corrugated corner fastener.

Fig. 11 is a section through one side wall and its junction with the bottom.

Similar reference characters indicate corresponding parts in all of the views.

This method is preferably practised on a previously prepared slab of wood. The wood preferred is so called Spanish or cigar box

cedar and the slab A may be made of three layers of cedar, 7, 8 and 9, the grain of the middle layer 8 lying crosswise of the grain of the exterior layers 7 and 9. The length of the prepared slab will be equal to the length of the desired box plus the combined height of the front and rear sides 2 and its width will be the width of the desired box plus twice the height of the end sides 2. After having selected a slab of the desired dimensions, one surface of it will be covered with a layer of lining paper or other fabric 12. The surface upon which this lining paper is cemented, destined to become the inside of the box, will be deemed to be the upper side of the slab. Fig. 1^a shows the condition of the blank after the paper lining 12 has been applied.

To perform the next step of the method, the blank may be turned over and strips 10, 11 of muslin, tough paper or other suitable flexible sheet material cemented to the under side as illustrated in Fig. 2. The center lines of these strips approximately outline the bottom and side walls of the box.

After the reinforcing strips 10 and 11 have been applied, the grooves 13 and 14 are cut into the upper surface of the slab, severing the lining paper 12 and extending part way through the slab. These grooves may be 90° in cross section, 45° each side of a perpendicular extending to the bottom. The grooves 13, 14, extend directly opposite and parallel with the reinforcing strips 10 and 11, and outline the bottom 1 and sides 2 of the box.

After the grooves have been cut, a flexible border strip 15 is applied on three edges of the blank as shown in Fig. 4. This border strip may be the usual paper border customarily found on cigar boxes and is generally of an ornamental character containing the name or trade mark of the maker or distributor of the cigars in the box.

After the border 15 has been applied the corner pieces 16 are cut away leaving a blank of cruciform shape, the parts 2, destined to constitute the side walls of the box, being connected to the bottom 1 by thin layers or ligamentary hinges of wood 13^a and 14^a and by the reinforcing strips 10 and 11 cemented over them.

After the corner pieces 16 have been re-

moved, as shown in this embodiment, the ends of the side walls have a 45° miter or bevel so that when the sides are raised to a position perpendicular to the bottom, the ends of the side walls meet to form a square mitered joint. The layers 13^a and 14^a, which connect the side walls to the bottom, are flexed and allow the side walls to be erected until the opposite faces 13^b and 14^b of the grooves meet, forming thus a mitered joint adjacent the connecting or ligamentary layer of wood.

The box may be made air tight and given superior strength by coating the beveled sides of the grooves including the beveled ends of the side walls 2 with glue or other cementitious coating composition. Paraffin, or other suitable coating or luting composition may be applied to the beveled surfaces which are brought together when the sides are raised to form the completed box body in order to make a tight box for the better preservation of its contents. A cement coating when used coats with the binding strips 10 and 11, the ligamentary layers 13^a and 14^a, referred to, and with the corrugated fastener, to be described presently to hold all parts of the box body securely together.

After the side walls have been erected and the beveled ends brought into contact they are secured together by driving the fastening 17 into the corners as illustrated in Figs. 7 and 8. The box is now complete excepting for the addition of the cover C and this should be fastened to the edge 3 of the back wall which has no edge binding 15, by means of a strip of fabric of suitable character.

By this method the lining, the reinforcing strips, and the ornamental border, are placed in position during the process of manufacture while the bottom and side walls of the box are still united in unfinished state in the flat slab. It is obvious that it is much more convenient to apply neatly the lining, border, reinforcing strips and glue or other coating composition (when used) at this time than it would be after the box is completed. The grain of the wood at the sides and bottom lies parallel with said sides and bottom. The registration of the parts is perfect when the sides are bent up and united to form the box;—there can be no displacement of parts. The operations necessary to make this box are simple, the process of manufacture is greatly facilitated; the box loses notching in strength but rather gains therein, and inaccuracies of arrangement, adjustment and alinement of the parts in assembling the box are unlikely. The method results in the rapid production of a neat, strong box suited to contain cigars of high grade.

Having thus described my invention what

I claim and desire to secure by Letters Patent is as follows:

1. The method of making a lined box which consists in cementing a lining material to a slab, cutting crossing grooves through the lining material and in the slab from edge to edge, severing the corner pieces lying within the angles formed by end portions of the crossing grooves, bending the blank thus formed along the grooves until the end edges of the side walls meet and securing the side walls together.

2. The method of making a box which comprises securing reinforcing strips crosswise of each other to a slab in position to outline the bottom of the box, cutting crossing grooves in the side opposite the reinforcing strips removing the corner pieces lying within the angles formed by end portions of the crossing grooves, bending the blank thus formed along the grooves until the end edges of the side walls meet, and securing the side walls together.

3. The method of making a box which comprises securing reinforcing strips crosswise of each other to a slab in position to outline the bottom of the box, cutting crossing grooves in the side opposite the reinforcing strips to outline said bottom, removing the corner pieces lying within the angles formed by end portions of the crossing grooves applying a coating composition to the sides of the grooves, bending the blanks thus formed along the grooves until the end edges of the side walls meet, and securing the side walls together.

4. The method of making boxes which consists in forming a slab of a length and width equal to the length and width of the bottom plus twice the height of the desired box, cutting crossing grooves in the slab from edge to edge so as to outline the bottom, applying flexible binding material to the edge, removing the corner pieces lying within the angles formed by end portions of the crossing grooves, bending the blank thus formed along the grooves until the end edges of the side walls meet, and securing the side walls together.

5. The method of making cigar boxes which consists in forming a wooden slab of a length and width equal to the length and width of the bottom plus the combined height of the end sides, and front and rear sides respectively, of the desired box, cementing flexible reinforcing tapes crosswise of each other in position to outline the bottom edges of the box, cementing a lining to the opposite face of the slab, cutting crossing grooves in the side opposite the tapes, removing the corner pieces of the slab within the angles formed by the end portions of the crossing grooves to form a cruciform blank.

6. The method of making a box which comprises preparing a slab of wood of a length and width at least equal to the length and width of the bottom plus the combined height of the end side walls and front and rear side walls respectively; securing flexible sheet material to the slab in position to overlap the bottom and side wall areas thereof, cutting crossing grooves in the slab oppo-

site the sheet material, removing the corner 10 pieces lying within the angles formed by end portions of the crossing grooves, bending the blank thus formed along the grooves until the end edges of the side walls meet and securing the side walls together. 15

In testimony whereof I affix my signature.

HENRY LEIMAN.
